(57) **CLAIM**

The ornamental design for a combined box cutter and
scissors, as shown and described.

DESCRIPTION

FIG. 1 is a right side elevation view of the combined box
cutter and scissors showing our new design, with the box
cutting element in its stored position;

FIG. 2 is a rear view thereof;

FIG. 3 is a left side elevation view thereof;

FIG. 4 is a front view thereof;

FIG. 5 is a top plan view thereof;

FIG. 6 is a bottom plan view thereof;

FIG. 7 is a right side elevational view thereof, with the box
cutting element in its open position;

FIG. 8 is a front view of FIG. 7; and,

FIG. 9 is a rear view of FIG. 7.
